ROCK DRILL

John C. Curtis, Garfield Heights, Ohio, assignor
to The Cleveland Rock Drill Company, Cleve-
land, Ohio, a corporation of Ohio

Application May 7, 1934, Serial No. 724,293

7 Claims. (Cl. 121—10)

This invention relates broadly to fluid actuated rock drills, but more particularly to the valvular mechanism for fluid actuated rock drills of the hammer type.

One object of this invention is to produce a simple valvular mechanism comprising a valve of positive and quick action provided with efficient wearing surfaces.

Another object of this invention is to provide a valvular mechanism for fluid actuated rock drills wherein the valve is adapted to control the admission of a portion of the fluid compressed within the cylinder to the bottom of the drilled hole being drilled, affording thereby an efficient hole cleaning device without increasing the motive fluid consumption of the machine.

Other objects and advantages more or less ancillary to the foregoing reside in the specific construction and aggroupment of the elements peculiar to this structure, as will become apparent from a more complete examination of this specification.

In the accompanying drawing illustrating the invention,

Figure 1 is a longitudinal sectional view of a rock drill embodying the invention.

Figure 2 is an enlarged longitudinal sectional view of the valvular mechanism shown in Figure 1, illustrating the valve positioned for permitting the admission of the pressure into one end of the cylinder.

Figure 3 is a view similar to Figure 2 illustrating the valve positioned for permitting the admission of the pressure fluid into the other end of the cylinder.

Referring to the drawing in which like symbols designate corresponding parts throughout the several views, 10 represents the cylinder of a rock drill having reciprocably mounted therein the piston 11 formed with a splined stem 12. Secured within the front end of the cylinder 10, there is a front bushing 13 accurately machined to slidably receive the stem 12, the latter being connected against relative rotation with a chuck 14 rotatably mounted within the front bushing 13, and extending into a front housing 15. Slidably mounted within the chuck 14, there is the shank 16 of a tool implement upon which the piston 11 is capable of delivering its blows.

Secured within the back end of the cylinder 10, there is a valve block 17 formed with a plurality of intercommunicating internal chambers 18, 19, and 20. Secured in press fit engagement within the rear end portion of the valve block 17, there is a valve bushing 21 formed with a

sleeved portion 22 extending into a valve cap 23 located in advance of the valve block 17. Reciprocably mounted within the valve block 17, there is a valve member 24 formed with a disc 25 movable into or out of engagement with the inner wall 26 of the chamber 18. Toward its inner end, the disc 25 is formed with two annular opposed faces capable of engagement with two opposed annular valve seats 27 and 28, the former protruding into the valve chamber 18 while the latter is a part of the valve cap 23. Extending from the inner end of the disc 25, the valve member 24 is formed with a sleeved portion 29 provided, intermediate its ends, with a relatively large annular external groove 30 and a relatively small internal flange 31, the latter being slidably mounted on the sleeved portion 22 of the valve bushing 21. To provide better guiding and wearing surfaces, the left inner wall of the valve sleeve 29 is slidably engageable with the valve bushing 21 extending therein, thus defining with the valve inner flange 31 a chamber 32. Similarly, the right inner wall of the valve sleeve 29 is slidably engageable with a protruding portion 33 of the valve cap 23, thus defining with the valve inner flange 31 a chamber 34. Leading from the valve sleeve groove 30 into the chamber 34, there is a restricted port 35, while a similar port 36 is provided through the disc 25.

The front or right end portion of the interior of the cylinder 10 is capable of constant communication with the chamber 19 through a plurality of front inlet passages 37, while the back or left end portion of the interior of the cylinder 10 is capable of communication with the chamber 18 through a plurality of rear inlet passages 38. Leading from the interior of the cylinder 10 to the atmosphere, there is an exhaust port 39. Again leading from the interior of the cylinder, there is a port 40 opening into the chamber 20, the latter being constantly connected with the chamber 32 through a plurality of passages 41.

Secured to the end of the cylinder by a pair of bolts, there is a back head 42 having rotatable therein a throttle valve 43 formed with a centrally disposed port 44 connected to the exterior of the throttle valve through a radially disposed port 45. Disposed between the valve block 17 and the back head 42, there is the common rotation mechanism comprising a ratchet ring 46, and rifle stem 47, the latter extending into the cylinder 10 through the valve bushing 21 for cooperation with the piston 12 in the well-known manner. Interposed between the ratchet ring 46 and the back head 42, there is a ratchet ring bearing plate 48 formed with an enlarged annular groove 49 capa-

ble of communication with the throttle valve port 45 through an orifice 50, and with the valve block chamber 18 through a plurality of ports 51.

Leading from the throttle valve 43 to the shank 16 of the tool implement, there is a port 52 in constant communication with the outer end of the valve sleeve portion 29 through a port 53 and annular groove 54.

The operation of the machine is as follows:

- 10 Assuming the valve member 25 to be positioned as illustrated in Figs. 1 and 2 with the throttle valve positioned as illustrated in Fig. 1, pressure fluid from the throttle valve is admitted into the annular groove 49 through the throttle valve passage 45 and port 50. From the groove 49, pressure fluid is admitted into the valve block chamber 18 via the plurality of ports 51, to act on the left side of the valve disc 25 for holding the valve on the valve seat 27. In this instance, 20 the marginal wall of the disc 25 is engaging the inner wall 26 of the chamber 18, preventing thereby the flow of the fluid around the disc. From the left side of the valve disc 25 the pressure fluid is gradually admitted on the right side 25 of the disc through the restricted port 36, reducing thereby the effective holding area on the left side of the disc to an area substantially equal to the area of the valve seat 27. Simultaneously, the pressure fluid is also admitted 30 into the chamber 34, through the restricted port 35, to act on the right side of the inner flange 31 tending to shift the valve toward the left. However, the effecting holding area on the left side of the valve disc 25 is large enough to resist 35 the action of the pressure fluid on the inner valve flange 31. From the chamber 18, the pressure fluid is free to flow into the chamber 19 via the clearance existing between the inner wall of the valve seat 27 and the valve groove 30, and 40 from the chamber 19 into the front end of the cylinder 18 through the ports 37. Pressure fluid admitted into the front end of the cylinder will act on the piston 11 to drive the latter toward the left. During the leftward movement of the 45 piston, the atmosphere within the left end portion of the cylinder compressed by the piston, will act on the front portion of the valve disc exposed thereto through the ports 38, thus tending, together with the pressure fluid acting on the left side of the inner flange 31, to shift the valve toward the left. The valve, however, will not 50 shift until the piston finally uncovers the exhaust port 39, permitting thereby the pressure fluid in the front end of the cylinder to exhaust to atmosphere and thereby causing a drop of pressure 55 on the left side of the valve disc 25.
- During the shifting of the valve, the marginal wall of the disc 25 does not leave the inner wall 26 of the chamber 18 previous to the engagement 60 of the inner end of the sleeved portion 29 with the inner wall of the valve seat 27, preventing thereby the simultaneous flow of the pressure fluid into the front and rear end of the cylinder through the passages 37 and 38.
- 65 When the valve is positioned as illustrated in Fig. 3, the pressure fluid admitted in the chamber 18 is free to flow around the disc of the valve to act on the right side thereof for holding the valve in its rearward position. From the right side of the disc, the pressure fluid is admitted 70 into the left end of the cylinder through the ports 38 to drive the piston to the right or against the shank 16 of the tool implement. The pressure fluid previously admitted in the chamber 75 34 for acting on the right side of the valve inner

flange 31 is now free to flow to the bottom of the hole being drilled via the chamber 19, valve groove 30, annular recess 54, ports 53 and 52 and the interior of the hollow tool implement 16.

During the rightward stroke of the piston, the latter will first uncover the port 40, thus admitting pressure on the left side of the inner valve flange 31 or into the chamber 32 via the port 40, chamber 20 and ports 41, tending thereby to shift the valve toward the left. However, the effective holding area of the right side of the valve disc 25 being greater than the area on the left side of the inner flange 31, the valve will not shift until the piston 11 uncovers the exhaust port 39, creating thereby a drop of pressure on the right side of the valve disc 25 permitting the shifting of the valve. During the rightward stroke of the piston, when the latter covers the exhaust port 39, the atmosphere, and possibly some motive fluid under relatively low pressure remaining in the right end of the cylinder, is compressed by the piston during its travel toward the right end of the cylinder. Heretofore, no provisions were made to relieve such compression, which obviously will retard the forward movement of the piston and consequently will prevent the latter to strike the tool implement with all the power generated during the forward stroke of the piston. In the present construction, the fluid within the right end of the cylinder normally compressed by the piston, is free to exhaust therefrom through the port 37, chamber 19, valve groove 30, annular recess 54, ports 53 and 52 to be admitted to the end of the shank 16 from where it will flow through the port formed in the tool implement to the bottom of the drilled hole for cleaning the latter. In this manner, the fluid compressed by the piston is not only permitted to exhaust from the front end of the cylinder, but is utilized for blowing the hole being drilled, affording thereby an efficient method and device for removing the chips from the bottom of the hole without increasing the motive fluid consumption of the machine. When the piston finally uncovers the exhaust port 39, the valve will trip in the position shown in Figs. 1 and 2 thus completing the cycle.

When it is desired to admit a supplemental amount of pressure fluid to the bottom of the drilled hole, the throttle valve may be rotated to permit the communication of the throttle port 45 with the port 52, preventing thereby the admission of the pressure fluid in the chamber 18. In this instance, the pressure fluid flowing through the port 52 is also admitted on the outer end of the valve sleeved portion 29 through the port 53 and similar recess 54. Pressure fluid thus admitted on the valve will have no other consequences than simply maintaining the valve in the position shown in Figs. 1 and 2.

Although the foregoing description is necessarily of a detailed character, in order to completely set forth the invention, it is to be understood that the specific terminology is not intended to be restrictive or confining and it is to be further understood that various rearrangements of parts and modification of structural detail may be resorted to without departing from the scope or spirit of the invention as herein claimed.

I claim:

1. In a rock drill, the combination of a cylinder having a fluid actuated piston reciprocable therein, of a hollow tool implement slidable within the front end of the machine, of a fluid actuated valve

- member reciprocable in time relation with said piston for controlling the admission of the piston actuating pressure fluid into said cylinder, a passage controlled by said valve member being open 5 thereby during the stroke of said piston in one direction for admitting compressed fluid from the interior of said cylinder to the bottom of the hole being drilled via said hollow tool implement, and being closed by said valve member during the 10 stroke of said piston in the other direction.
2. In a rock drill, the combination of a cylinder having a fluid actuated piston reciprocable therein, of a hollow tool implement slidably within the front end of the machine, of valve controlled passages for alternatively admitting pressure fluid into the end portions of said cylinder for actuating said piston, of an exhaust port through which the pressure fluid admitted into said cylinder 15 may exhaust therefrom, one end portion of said cylinder constituting a cushion chamber wherein the air remaining therein subsequent to the exhaust of the pressure fluid therefrom through said exhaust port is normally compressed by said piston during its stroke toward said one end portion, means for admitting said compressed air via the interior of said tool implement to the bottom of the hole being drilled for cleaning the latter during the stroke of said piston toward said one 20 end portion, and means for closing said cushion chamber from said tool implement during the movement of said piston away from said one end portion.
3. In a fluid actuated rock drill, the combination of a cylinder having a piston reciprocable therein, a hollow tool implement slidably mounted within the front end of the rock drill, a valve block, front and rear inlet passages leading from said valve block to the end portions of said cylinder, a valve reciprocable within said valve block for controlling the flow of the pressure fluid through said inlet passages, said valve comprising a disc having a sleeve extending therefrom, an inner flange within said sleeve, the opposed sides of said disc and flange constituting 25 pressure areas on which pressure fluid may be admitted for actuating said valve, said valve being shifted in one position by the pressure fluid constantly admitted on one side of said disc and intermittently admitted on the corresponding side 30 of said inner flange, the shifting of said valve in the other direction being responsive to the compression from the rear of the cylinder intermittently admitted on the other side of said disc and by the pressure fluid intermittently admitted 35 on the corresponding side of said inner flange, and means for admitting and exhausting pressure fluid to and from the sides of said disc and flange, said means including one passage for exhausting the pressure from one side of said flange to the 40 bottom of the hole being drilled for cleaning the latter via the interior of said hollow tool implement.
4. In a rock drill, the combination of a cylinder 45 having a fluid actuated piston reciprocable therein, the end portions of said cylinder constituting forward and rearward pressure chambers within which fluid is admitted for actuating said piston, a hollow tool implement slidably mounted within the front end of the machine, and means whereby fluid from said forward pressure chamber is admitted to said tool implement during a portion of the stroke of said piston toward said last mentioned chamber, said means preventing fluid from 50 said forward pressure chamber to be admitted therefrom to said tool implement after the reversal of said piston stroke.
5. In a rock drill, the combination of a cylinder 55 having a fluid actuated piston reciprocable therein, the air within one end portion of said cylinder being normally compressed therein by the piston during the stroke thereof toward said one end portion, a tool implement slidably mounted within the front end of the machine, and means whereby said air compressed within said one end portion of the cylinder is admitted to said tool implement during a portion of said piston stroke, said means preventing said compressed air from 60 said one end portion of the cylinder to be admitted therefrom to said tool implement during the stroke of said piston away from said one end portion.
6. In a rock drill, the combination of a cylinder 65 having a fluid actuated piston reciprocable therein, the end portions of said cylinder constituting forward and rearward pressure chambers within which fluid is admitted for actuating said piston, a hollow tool implement slidably mounted within the front end of the machine, a fluid conveying 70 passage affording the communication of said forward pressure chamber with said tool implement, and a fluid actuated valve movable in open position relative to said passage during a portion of the stroke of said piston toward said last mentioned chamber, and in a closed position relative to said passage during the primary major portion of said piston stroke toward the other of said 75 pressure chambers.
7. In a rock drill, the combination of a cylinder 80 having a fluid actuated piston reciprocable therein, the end portions of said cylinder constituting forward and rearward pressure chambers within which fluid is admitted for actuating said piston, an exhaust port controlled by said piston through which the fluid from said chambers may exhaust, a hollow drill steel slidably mounted within the front end of the machine, a fluid conveying 85 passage affording the communication of said forward pressure chamber with said tool implement, and automatically operated valve means movable to a position to open said passage during a portion of the stroke of said piston toward said forward pressure chamber and to a position to close said passage during the travel of said piston over said exhaust port on its way toward said 90 rearward pressure chamber.

JOHN C. CURTIS.
